UNITED STATES PATENT OFFICE

167,176

CORNICE

Edward E. Schaefer, Oak Park, Ill.

Application January 9, 1952, Serial No. 17,971

Term of patent 7 years

(Cl. D21—6)

To all whom it may concern:

Be it known that I, Edward E. Schaefer, a citizen of the United States, residing at Oak Park, in the county of Cook, State of Illinois, have invented a new, original, and ornamental Design for a Cornice, of which the following is a specification, reference being had to the accompanying drawing, forming a part thereof, wherein:

Figure 1 is a front elevational view of the cornice showing my new design;

Figure 2 is a top plan view of the cornice shown in Fig. 1;

Figure 3 is an end elevational view of the cornice; and

Figure 4 is a cross-sectional view taken along the line 4—4 of Figure 1.

I claim:

The ornamental design for a cornice, substantially as shown.

EDWARD E. SCHAEFER.
